UNITED STATES PATENT OFFICE

98,171

DESIGN FOR A HAND BAG

Isidore Lending, New Bedford, Mass., assignor to Sol Mutterperl, Incorporated, New York, N. Y.

Application November 29, 1935, Serial No. 59,806

Term of patent 3½ years

To all whom it may concern:

Be it known that I, Isidore Lending, a citizen of the United States, residing at New Bedford, in the county of Bristol and State of Massachusetts, have invented a new, original, and ornamental Design for Hand Bags, of which the following is a specification, reference being had to the accompanying drawing, forming part thereof.

Figure 1 is a perspective view of the hand bag in closed position showing my new design.

The other side of the hand bag is like the side shown in Figure 1 except for the opening member.

I claim:

The ornamental design for a hand bag, as shown and described.

ISIDORE LENDING.
